DESIGN FOR A POWDER BLENDER

James R. Clarke, Oneida, N. Y.

Application January 30, 1947, Serial No. 136,545

Term of patent 3½ years

(Cl. D86—10)

To all whom it may concern:

Be it known that I, James R. Clarke, a citizen of the United States, residing at Oneida, in the county of Madison and State of New York, have invented a new, original, and ornamental Design for a Powder Blender, of which the following is a specification, reference being had to the accompanying drawing, forming part thereof.

In the drawing

Fig. 1 is a side view of a powder blender showing my new design;

Fig. 2 is a top plan view of my new design.

The side of the powder blender not shown in the drawing is substantially like the side disclosed.

I claim:

The ornamental design for a powder blender, substantially as shown and described.

JAMES R. CLARKE.
